UNITED STATES PATENT OFFICE

DE WITT CLINTON TYLER, OF CHICAGO, ILLINOIS

SOAP DISPENSING APPARATUS

Application filed April 7, 1931. Serial No. 528,423.

My present invention has reference to a dispensing apparatus and has for its primary object the provision of a device for dispensing paste soap in ribbon-shape without necessitating the opening of the container for the soap.

A further object is the provision of a paste soap dispensing apparatus in which the soap is ejected in ribbon shape from the bottom thereof by the manipulation of a handle or lever associated with the apparatus, one wherein the soap seals the opening or passage through which it is designed to be ejected, and one wherein the manifest disadvantages of removing the top from the container to obtain access to the soap is entirely dispensed with.

A still further object is the provision, in a paste soap dispensing apparatus, of means in the apparatus, operated exteriorly thereof for sweeping over the outlet opening in the bottom of the apparatus, causing the soap to be ejected through such opening at an easy flow and at a uniform thickness, and likewise in a desired quantity and thereby obviating the waste of the soap.

A still further object resides in the construction of an apparatus for this purpose, the manner in which the same is removably supported in a vertical position, the manner in which the dasher or ejector is removably mounted upon the operating shaft, the manner in which said shaft is turned exteriorly of the container, and the manner in which the paste soap is ejected in ribbon formation at an angle with respect to the bottom of the apparatus.

To the attainment of the foregoing the invention also consists in other novel features of construction, combination and operative association of parts, one satisfactory embodiment of which is disclosed by the accompanying drawing.

In the drawing:

Figure 1 is a side elevation of the improvement, with parts broken away and parts in section.

Figure 2 is a top plan view thereof with parts broken away.

Figure 3 is a detail sectional view approximately on the line 3—3 of Figure 1.

Figure 4 is a similar sectional view approximately on the line 4—4 of Figure 1.

My improvement is primarily designed for use in machine shops, automobile repair shops, garages or the like, in which places the hands of the mechanics become soiled by grease and tar. Such substance cannot be removed by ordinary soaps and there is on the market a number of semi-plastic or paste soaps in which fine sand or powdered pumice stone is an important constituent. This class of soap is marketed either in a fibre or metal container and when required for use it is necessary that the top of the container be removed and that the user place his hand in the container to obtain therefrom a desired quantity of the soap. Because of the grease or tar on the hands of the mechanic the top of the container is hard to remove but when removed the mechanic grasps a hand full of the soap which, in the majority of instances is more than required and, therefore, results in waste. Also the cans or containers are placed indiscriminately about the shop so that time is lost in locating the same. It will be noted as the description progresses that with my improvement the simple manipulation of the handle arranged exteriorly of the casing will cause the paste soap to flow in ribbon shape through the bottom of the container in desired quantities so that the difficulty of obtaining soap from the container and the waste created thereby will be effectively overcome.

The container disclosed by the drawing may be of the ordinary construction, that is, the same may be of fibre or of metal. The container is of cylindrical formation and is indicated by the numeral 1. The container is designed to be supported in a vertical position and, therefore, I secure upon the wall of the shop or an upright the ends of a spring strap 2. The body of the strap is rounded upon itself. The offset ends of the strap have the securing means therefor also passing through the offset ends of an outwardly arched spring saddle 3, and the outer portion of the saddle is bowed outwardly, as

at 4, to contact with the support 5. Thus when the cylindrical container is inserted in the holding strap the spring saddle will exert a frictional engagement thereagainst 5 for effectively sustaining the container in vertical position.

The top of the container 1 is open and is closed by a removable flanged cap 6, the said cap having its center opening therethrough 10 surrounded by an annular flange 7. The bottom of the container is crimped or bent at the center thereof to form the same with a concaved bearing 8 for the pointed end 9 of a hexagonal shaft 10. The shaft 10 extends 15 through the flange 7 and finds a bearing in said flange. The shaft is provided with a longitudinal and transverse slot which extends from a slight distance above its journal end 9 which terminates a suitable distance 20 from its outer end. The slot is designed to receive therein a plate that provides a dasher 11. The dasher has its lower edge centrally formed with a substantially V-shaped notch 12 whose inner wall, indicated 25 by the numeral 13, is straight and the outer or top edge of the dasher is curved, as at 14, the curvature being struck from the center of the straight wall 13 provided by the notch. By this arrangement it will be noted 30 that the tilting of the dasher plate permits of the same being received in the opening provided therefor in the shaft 10 and obviously permits of the removal of the dasher from the shaft.

35 The bottom of the container is provided with a slot or opening that affords a delivery mouth 15 for the paste soap in the container. The mouth is preferably formed by slitting the bottom of the container and by 40 bending the bottom in opposite directions from the said slit to provide an inwardly directed angle flange 16 and an outwardly directed angle flange 17. The flange 16 affords a knife or cutter and the flange 17 provides a directing lip for the delivery mouth. 45 The lower and straight edge of the dasher 11 is disposed only a slight distance away from the knife or cutter flange 16, so that the turning of the shaft and the like turning 50 of the dasher will cause the latter to sweep over the knife and thereby forcibly eject through the delivery mouth 15 a quantity of the paste soap in ribbon formation and of a desired width and thickness. The soap is 55 directed along the lip 17 and is, therefore, delivered at an angle with respect to the container.

On the upper end of the hexagonal shaft 10 there is the hollow headed end 18 of a lever 19. The head is freely journaled on the outer end of the shaft 10 and rests on the flange 7 of the closure 6. In the hollow head there is a ratchet wheel 19 that has a hexagonal bore to receive the shaft 10 there-through and to lock the said wheel on the

shaft. This ratchet wheel is engaged by a spring pawl 20 that is fixed in the hollow head 18. The hollow head 18 is covered by a cap plate 21 secured thereon by removable means 22. The end of the shaft passes 70 through a round opening in the cap plate 21 and terminates in a line with the cap plate. The upper end of the shaft and the cap have arranged thereover a washer 23, which is contacted by the head of the bolt or screw 24 that is threadedly received in the shaft 10.

The lever 19 is designed to be oscillated in a horizontal direction to cause the pawl 20 to engage with the teeth of the ratchet wheel 19 to impart a turning to the shaft 10 and a like turning to the dasher 11. The lever projects a suitable distance beyond the container so that the same can be readily grasped by the operator and, by manipulating the lever a desired quantity of paste soap may be delivered from the container in a manner as previously described. The paste soap is ejected from the container only in desired quantities so that there will be no waste. 80 The soap normally seals the delivery mouth 15 so that the container is practically airtight and thus the contents thereof are indefinitely preserved. The dasher, cap or closure and the lever may be simultaneously removed from the container when the same is to be refilled. The container may remain a permanent fixture and receive therein the usual paste soap containers whose top and bottom are removed or the said container 85 may be of the ordinary type in which paste soap is commercialized.

The construction, operation and advantages of my improvement will, it is thought, be readily understood and appreciated by those skilled in the art to which such invention relates so that further description will not be required. Obviously I do not wish to be restricted to the precise details herein set forth and, therefore, hold myself entitled to 105 make such changes therefrom as fairly fall within the scope of what I claim.

Having described the invention, I claim:

1. A container for paste soap or the like having a bearing in its bottom and an opening adjacent the bearing whose sides are provided with respective inwardly and outwardly directed angle flanges, a removable flanged top for the container having an opening in the center thereof surrounded by a flange, a shaft having a pointed end received in the bearing, and the said shaft likewise extending through the flange of the closure, said shaft being slotted longitudinally, a dasher plate having its lower end notched and its upper edge struck at a curvature, removably received through the opening, and an operating lever for the shaft. 110

2. A container for paste soap or the like having a bearing in its bottom and an open- 115

ing adjacent the bearing whose sides are provided with respective inwardly and outwardly directed angle flanges, a removable flanged top for the container having an opening in the center thereof surrounded by a flange, a shaft having a pointed end received in the bearing, and the said shaft likewise extending through the flange of the closure, said shaft being slotted longitudinally, a 10 dasher plate having its lower end notched and its upper edge struck at a curvature, and removably received through the opening, an operating lever having a hollow head freely journaled on the outer end of the shaft 15 and resting on the flange of the closure, a ratchet wheel fixed on the said end of the shaft and received in the hollow head, a pawl in the hollow head to engage with the ratchet, a closure plate for the hollow head 20 and means removably securing the head on the shaft.

3. A device for the purpose set forth, a longitudinally slotted shaft, a dasher plate supported and frictionally engaged in the 25 slot, said dasher having its lower edge formed with a centrally located V-shaped notch in its lower edge and its upper edge struck at a curvature from the center of the notch and the distance between the notch and 30 the curved edge being approximately equal or slightly less than the length of the slot.

4. A container for paste soap or the like having a slot in the bottom thereof with one edge of the slot disposed inwardly of the 35 bottom, a shaft journaled within the container and having a longitudinal slot, a dasher plate arranged in the slot and having a centrally located notch in its lower edge, whereby said edge terminates in close prox- 40 imity to the bottom of the container, the upper edge of the dasher plate being curved and engaging the adjacent end of the slot of said shaft, and means for rotating said shaft.

In testimony whereof I affix my signature.

45 DE WITT CLINTON TYLER.
